UNITED STATES PATENT OFFICE

2,593,016

SANITARY SMOKING PIPE

Albert Dressler, Jr., and Arthur E. Fowler,
Elmira, N. Y.

Application June 21, 1948, Serial No. 34,164

1 Claim. (Cl. 131—225)

1

This invention relates to a sanitary smoking pipe.

It is an object of the present invention to provide a sanitary smoking pipe wherein the stem parts can be disassembled so that access can be had to the interior surface of the stem parts and wherein the mouthpiece may be separated to provide access to the passage through them and wherein the parts can be reassembled and retained without need of a great number of fastening parts and without the use of threads on the parts.

Other objects of the present invention are to provide a sanitary smoking pipe which can be disassembled for the purpose of cleaning the same, which is of simple construction, inexpensive to manufacture, easy to clean, light in weight and efficient in operation.

For other objects and for a better understanding of the invention, reference may be had to the following detailed description taken in connection with the accompanying drawing, in which

Fig. 1 is a top plan view of the pipe assembled.
Fig. 2 is a side elevational view of the pipe.

Fig. 3 is an enlarged longitudinal sectional view of the pipe taken on line 3—3 of Fig. 1.

Fig. 4 is a transverse sectional view taken on line 4—4 of Fig. 3.

Fig. 5 is a perspective view of the external sleeve with the fastening pin.

Fig. 6 is a collective view of the internal separable stem parts and of the closure plug for the outer end of the stem.

Fig. 7 is a collective view of the separable mouth piece parts.

Fig. 8 is a side elevational view of a modified form of mouth piece.

Fig. 9 is a top plan view of the mouth piece shown in Fig. 8.

Fig. 10 is an end elevational view of the mouth piece shown in Fig. 8.

Referring now to the figures, 15 represents a pipe bowl which has a bottom 16 and a hole 17 extending from one side to the other to receive pipe stem assembly 18 formed of an external sleeve 19 and separable internal sleeve parts 21 and 22 and separable mouth piece parts 23 and 24. The stem assembly 18 passes through the opening 17 to the opposite side of the pipe bowl and a plug 25 having a sleeve projection 26 closes the end of the assembly.

The external sleeve 19 has holes 27 through which smoke passes from the pipe bowl 15 to the interior of separable internal sleeve parts 21 and 22 and the upper sleeve part 21 has holes 28

2

aligned with the holes 27 of the external sleeve part 19 to accomplish the above. The internal sleeve, which consists of the parts 21 and 22, constitutes an inner lining for the external sleeve 19, whereby any accumulation of matter is deposited on the inner surface of the internal sleeve which can be readily removed and cleaned. The stem assembly is held together by a pin 29 and is held against rotation within the pipe bowl 15 by an enlargement 31 on the pin that is seated in a recess 32 in the pipe bowl and extending from the top of the opening 17 thereof. The pin 29 projects through an opening 14 in the sleeve part 19 and also through a registering opening 12 in the part 21.

The mouth piece part has a tip enlargement 33 which has a recess 34 into which the end of the part 23 extends and is retained. The parts 23 and 24 also have projections 36 and 37 respectively adapted to enter the internal stem parts 21 and 22. The mouth piece parts have shoulders 38 which abut the ends of the sleeves. The stem parts are preferably made of light weight aluminum while the mouth piece parts may be formed of plastic.

It will be apparent that the parts can be readily disassembled. Plug 25 is removed and thereafter the stem assembly can be pulled from the pipe bowl 15 and the pin 29 released so that the sleeve 19 can be separated from the sleeve parts 21 and 22 and the mouth piece assembly withdrawn from the sleeve parts and the parts thereof separated from one another. The mouth piece parts have grooves 39 forming the smoke passage therefor. These grooves can be thoroughly cleaned when the parts have been separated and likewise the interior faces of the sleeve parts 21 and 22 can be scoured.

Referring in detail to Figures 8, 9 and 10 of the drawings, there is shown a modified mouthpiece. This mouthpiece includes a main part 41 that is provided with a dovetailed groove 42 for snugly and slidably receiving a closure or key part 43. These parts each have longitudinally-extending, 45 semicylindrical grooves 44 and 45 which coact to provide the smoke passage. The part 41 also has a portion 11 which is of less diameter than the main portion of the part 41. The part 43 has an extension 46 that projects beyond the adjacent 50 end of the portion 11 of part 41 so as to provide a handle portion which can be grasped in order to remove the part 43 from the part 41. The part 41 is provided with an enlarged tip portion 47 and the tip portion has the usual inner, tapered recess 55 48 that communicates with the smoke passage.

The part 43 can be slid out of engagement with the part 41. The part 41 has a shoulder 49 that is adapted to abut the complementary end of the sleeve assemblage.

While various changes may be made in the detail construction, it shall be understood that such changes shall be within the spirit and scope of the present invention as defined by the appended claim.

We claim:

A smoking pipe comprising a bowl having a passage extending from one side to the other thereof, a pipe stem assembly formed of separable internal and external parts, the assembly being adapted to extend into the passage in the pipe bowl, a mouth piece formed of separable parts and adapted to be secured to the stem assembly, a pin adapted to be extended through the stem assembly parts to keep them angularly aligned, said pipe bowl having a recess extending radially from one end of its passage, said pin having a projection fitting the recess and adapted to prevent the angular displacement of the stem assembly relative to the pipe bowl.
